UNITED STATES PATENT OFFICE.

WM. L. WILLIAMS, OF NEW YORK, N. Y., ASSIGNOR TO HIMSELF AND THOS. J. O'CONNOR, OF SAME PLACE.

MACHINE FOR BUNDLING KINDLING-WOOD.

Specification of Letters Patent No. 30,790, dated November 27, 1860.

To all whom it may concern:

Be it known that I, WILLIAM L. WILLIAMS, of the city and State of New York, have invented, made, and applied to use 5 certain new and useful Improvements in Machinery for Bundling Kindling-Wood; and I do hereby declare that the following is a full, clear, and exact description of the construction and operation of the same, 10 reference being had to the annexed drawing, making part of this specification, wherein—

Figure 1 is a plan and Fig. 2 is a vertical section showing my improvements.

15 Similar marks of reference denote the same parts.

My present invention relates to improvements in the various parts of a machine for bundling kindling wood, which are intended 20 specially as additions to Letters Patent granted to me under date of May 8th, 1860, and can be used conjointly with parts set forth therein, or may be used separately or 25 with other machines for bundling kindling wood.

The kindling wood in its split form is loose, and openings occur in the same at different places, rendering the mass in the trough of the splitting machine unfit for 30 making up directly into bundles, or some bundles would have more wood in them than others. For this reason a ring or box has been used for the wood to be packed into by hand, but if the attendant did not 35 completely fill the same by the time the machine conveyed away said ring or box, the bundle was imperfect. To obviate this difficulty I make use of a wood conveyer A, formed with several openings into which 40 the wood is packed by the attendants, and said conveyer is moved intermittently to the delivery place. Several boys can be employed in packing the wood into said openings in order that they may be thoroughly 45 filled by the time they arrive successively to the place at which the wood is conveyed away to be compressed into a bundle.

The wood conveyer A, may be moved by 50 any suitable mechanism connected with the other parts of the machine; and B is a bed on which the lower ends of the pieces of kindling wood rest while the bed is moving.

a, is a slide of metal upon which the wood rests in the bundle that is ready for delivery. This slide is pulled away from under the wood by hand or automatic machinery and the bundle or mass of wood drops down or is forced into the trough b, through which it is conveyed to be compressed into 55 a bundle by the means hereafter set forth or any suitable mechanism. For this purpose I make use of the semi circular ended slide c, actuated by hand or otherwise that forwards the wood through the trough b 60 to the bundling apparatus; d, is a roller which by its own weight or springs or levers presses down the pieces of wood that 65 may stand up above the others.

In bundling kindling wood there are always 70 pieces of bark and splinters of wood which accumulate and tend to obstruct the machine. I therefore provide an opening d', at the end of the raceway through which all pieces laying on the bottom of the trough 75 are forced out, and in case any piece of wood falls down it also is forced out through this opening and injury to the machine is prevented. The mass of wood as forced along in a trough is apt not to form a good round 80 bundle upon the side opposite to that from which the wood moves, because said wood compresses and jams against this side instead of sliding along the same, hence notches and segmental cavities are left in 85 the bundle at this point. To obviate this I make use of an inclined side e, to the trough, at the end thereof, which as the wood is raised, tends to gather the same more compactly. 90

f is a plunger or follower in the bottom of the trough b, over which the wood is pressed by the slide c, and which in lifting up (as in my said patent of May 8th, 1860) carries the bundle of wood through the ring 95 opening 1, 1, where it is to be pressed by slides such as in my said patent or other suitable means. This follower f may be raised by any suitable mechanism and has a shield plate 2, to prevent chips passing down 100 between the follower and the bottom of the trough; and in case too much wood is in the trough for one bundle I make use of the separator g of a semi circular form and sharp at the upper end which not only splits 105 off and separates the surplus wood, but forms

a guide for the wood as pressed up to form the bundle. This separator or knife may be moved by a cam or other mechanism or by a hand lever.

5 The wire with which the bundle is confined is twisted in the jaw *i*. This jaw is formed in a two-part shaft, the lower part 3, being fitted to revolve in the standard *k*, while the upper part 4, has an endways sliding motion as well as the revolving. The operator lays the wire around the bundle passing the ends between the studs 5, 5, and turning them off as seen by the red line Fig. 1. The part 4, is then slid along and 10 the fingers (*i*), at the end thereof entering between and on each side of the studs 5, 5, hold the wire firmly while twisted by the revolution of the whole jaw; and the ends of the wires lift off the plates or studs 5, 5, 15 as the bundle is taken from the machine.

What I claim and desire to secure by Letters Patent, is—

1. A wood carrier A, formed with several

receptacles into which the wood is packed as set forth, and from which it is delivered to 25 be compressed into a bundle.

2. The slides *a* and *c*, to deliver the wood into the trough and convey the same to the compressing part of the machine as set forth.

3. The opening *d'*, at the end of the trough 30 *b*, for the purposes set forth.

4. The inclined side *e*, at the end of the trough for the purposes and as specified.

5. The shield 2, attached to the follower *f*, 35 for the purposes set forth.

6. The jaw *i*, formed and acting as set forth to receive hold and twist the wire that surrounds the bundle as specified.

In witness whereof I have hereunto set my signature this twenty first day of Sep- 40 tember 1860.

W. L. WILLIAMS.
